UNITED STATES PATENT OFFICE.

FRED MICHAELIS, OF BARTLESVILLE, OKLAHOMA.

OPERATING MECHANISM FOR ANNUNCIATING SYSTEMS.

1,073,357.

Specification of Letters Patent. Patented Sept. 16, 1913.

Application filed February 11, 1911. Serial No. 608,073.

To all whom it may concern:

Be it known that I, FRED MICHAELIS, a citizen of the United States, residing at Bartlesville, in the county of Washington 5 and State of Oklahoma, have invented certain new and useful Improvements in Operating Mechanism for Annunciating Systems; and I do hereby declare the following to be a full, clear, and exact description of 10 the invention, such as will enable others skilled in the art to which it appertains to make and use the same.

This invention relates to new and useful improvements in operating mechanism for 15 annunciating systems, and other like devices.

An object is the provision of a suitable 20 clock controlled mechanism which is electrically connected to a bell or series of bells and which will audibly give notification 25 of the time at different intervals or periods during the day by ringing the said bell or series of bells for different length periods of time.

Another object of this invention is to 30 improve and simplify devices of this character, rendering them comparatively simple and inexpensive to manufacture, reliable and efficient in use and readily operated.

In effecting these several desiderata, this 35 invention resides in the novel features of construction, formations, combinations and arrangements of various elements to be hereinafter more fully described, claimed and illustrated in the drawing in which:

Figure 1 is a front elevation of a clock having my invention applied thereto; Fig. 2 is a plan view of the supporting plates and their connections; Fig. 3 is a vertical 40 longitudinal sectional view taken on the line $b-b$ of Fig. 2. Fig. 4 is a vertical longitudinal sectional view taken on the line $b-b$ of Fig. 2 but looking in the opposite direction from Fig. 3. Fig. 5 is an end 45 view of the mechanism illustrated in Fig. 2; Fig. 6 is a plan view of one of the longitudinal disks and the wheel engaging the same; Fig. 7 is a fragmentary plan view of the plate and spring contacts supported 50 thereon; Fig. 8 is a detail perspective view of one of the spring contacts.

Referring to the corresponding figures of the drawings by similar characters of reference the numeral 1 designates generally a 55 clock casing or housing comprising front

and rear walls 2 and 3 connected at their opposite vertical edges by side walls 4, and at their opposite ends by a cap or upper closure 5, and a base or lower closure 6. The front wall 2 has formed therein a substantially rectangular shaped opening 7 closed by a glass paneled door 8 hinged as at 9 to one edge of the closure, and affording a means whereby access may be had to the 60 clock 10 when desired.

A pair of transversely extending supporting plates 11 and 12 are bolted or otherwise secured in vertical planes and in spaced parallel relation to each other within the casing 1 upon the base 6 and are retained 70 against displacement by sleeves 13 located upon tie rods 14 which extend through apertures 15 formed in the said plates.

A vertically disposed power transmitting rod 16 is rotatably mounted in suitable 75 brackets or bearings 17 extending from the outer face of the plate 12 and supports keyed to its upper terminal a beveled pinion 18 which meshes with a similar pinion 19 geared in any convenient manner to the 80 shaft 20 of the minute hand 21 of the clock 10. A horizontally disposed disk 22 is keyed to the lower end of the shaft 16 and serves to assist in controlling the hereinafter to-be-described elements. A beveled pinion 23 85 is keyed to the shaft 16 slightly above the disk 22 and meshes with a similar pinion 24 carried by the rearwardly extending terminal of a shaft 25 journaled at its opposite ends in the plates 11 and 12. The intermediate portion of the shaft has splined thereon a worm 26 the spirally wound threads 27 of which mesh with the teeth of a spur pinion 28 carried by a vertical shaft 29 the opposite reduced ends of which are journaled 90 in a pair of inwardly extending parallel superimposed arms 30 formed upon a supporting plate 31 while to this said shaft 29 at a joint below the spur pinion 28 is fixed a horizontally disposed disk 32 similar to 100 the beforementioned disk 22.

A spring actuated shaft 33 is journaled between the plates 11 and 12 and is extended at the end adjacent the plate 11 and squared as at 34 to provide a grip for a key not 105 shown thereby providing a means for winding this said shaft 33. A gear wheel 34^a is fastened to the shaft 33 and adapted to mesh with a pinion 35 carried by the shaft 25 which connection serves to gradually ro- 110

tate the shaft 25 through the medium of a spring 36 attached at one end of the shaft 33 and at its opposite end to a convenient joint upon the plate 11. The rotation of the shaft 25 is not dependent upon the shaft 33 but is merely assisted and in reality receives motion through the before mentioned vertical shaft 16 and clock 10.

A shaft 37 is journaled substantially intermediate of the plates 11 and 12 and carries keyed to the end adjacent the plate 12 a hub 38 provided with a plurality of radially extending arms 39 the offset terminals 40 of which are adapted to rest upon the disk 22 and pass through the slots 41 formed therein upon the rotation of the said shaft 16. This shaft 37 is so connected with the minute hand that the movement of the disk in a position to permit of the passage of the arms 39 therethrough requires the space of five minutes. A disk 42 is keyed to the opposite end of the shaft 37 and is graduated and numbered with characters 43 indicating the time in minutes from 5 to 60 inclusive. A sleeve 44 is rotatable upon the shaft 37 and has formed upon one end thereof a hub 45 similar to the hub 38 and carries a series of arms 46 similar to the arms 39 the offset ends 47 of which engage the disk 32 and pass through the slots 48 formed therein in the same manner as the before-mentioned arms. The disk 32 is so connected to the clock as to move one space each hour permitting the disk 49 carried by the sleeve 44 to move one space each hour. This disk is graduated in spaces bearing the numbers from 1 to 12 inclusive indicating hours.

In order to provide a means for rotating the shaft 37 and sleeve 44 a shaft 50 is journaled between the ends of the plates 11 and 12 and carries a sleeve 51 upon one end thereof the end of which together with the shaft 50 is squared to provide a means whereby they can be rotated by suitable keys not shown. Springs 52 are attached to the sleeve 51 and shaft 50 and to convenient parts upon the plates 11 and 12 and serve to impart a rotary movement to the shaft 37 and sleeve 44 through the medium of suitable gear wheels 53 and intermeshing pinions 54.

A plate 55 is secured to the lower edge of the plate 11 and extends outwardly therefrom supporting a pair of contact springs 56 and 57 which springs are provided with loops 58 adapted to engage screws or the like 59 for the purpose of preventing their undesired displacement. The disks 42 and 49 are provided with outwardly extending pins 60 and 61 adapted to engage the upwardly curved ends 62 of the spring contacts and either make or break the contact upon the rotation of the said disks.

The ends of several of the pins are bent laterally as at 63 to provide a means where-

by the bells 64 will be caused to ring for a longer period of time by their engagement with the said spring contacts 56 and 57.

Conductors 65 and 66 are connected to the eyes 67 and 68 formed upon the springs 56 and 57 one of which is broken between its ends as at 69 for connection with one or more batteries 70.

From the foregoing disclosures taken in connection with the accompanying drawings 75 it will be manifest that a clock controlled annunciating system is provided for which will fulfil all of the necessary requirements of such a device.

Having thus fully described this invention 80 what I claim as new and desire to protect by Letters Patent is:

1. The combination with a time registering mechanism, of a rotatable operating shaft connected thereto, a supporting means, 85 shafts journaled within the supporting means, means for intermittently rotating the said shafts, disk supporting shafts journaled in the supporting means, disks carried by the disk supporting shafts, pins projecting from 90 the disks, offset extensions provided upon the pins, contacts secured to the supporting means and engaging the pins and their offsets, and bells electrically connected to the contacts. 95

2. The combination with a time registering mechanism, of an operating shaft connected thereto, a supporting means, shafts journaled within the supporting means, means for rotating several of the said shafts, 100 slotted disks keyed to several of the shafts, arms projecting radially from several of the shafts and resting upon the said disks, means for rotating the shafts carrying the arms, disks keyed to the shafts carrying the 105 arms, said disks adapted to be rotated upon the rotation of the slotted disks, pins projecting from the disks carried by the arm-supporting shafts, offset extensions provided upon the pins, contacts secured to the supporting means and engaging the pins and their offsets, and bells electrically connected to the contacts. 110

3. The combination with a time registering mechanism, of a rotatable operating 115 shaft connected thereto, a supporting means, shafts rotatably mounted within the supporting means, slotted disks keyed to several of the said shafts, arms carried by several of the said shafts and adapted to rest upon 120 the slotted disks, disks keyed to the arm-supporting disks, springs engaging the arm-supporting shafts and adapted to force the arms into engagement with the disks for the purpose of permitting said arm-supporting 125 shafts to be rotated when the disks are rotated through the time registering mechanism, pins extending from the disks mounted upon the arm-supporting shafts, a plate mounted beneath said disks, spring contacts 130

secured to said plates and engaging the pins, a series of bells, conductors connecting the bells with the contacts, and a battery engaging one of said contacts for the purpose of 5 ringing the bells upon engagement of both contacts with one of the pins carried by each disk.

4. In a device of the character described, the combination with a casing of a clock located therein, a pair of plates within said casing, a shaft rotatably connected with the said clock, a pinion keyed to this shaft, a disk keyed to this shaft, a shaft rotatably mounted between the said plates, a pinion 10 carried by this shaft for engagement with the pinion carried by the clock-operated shaft, a worm secured to this shaft, a worm wheel engaging this worm, said worm wheel being located upon the shaft which is journaled in brackets carried by one of the plates, a disk secured to this last-mentioned shaft, another shaft journaled between said plates, a sleeve mounted thereon, wheels carried by this last-mentioned shaft and sleeves 15 located thereon, said wheels being provided with radially extending arms adapted to engage the faces of this said disks, and upon

the rotation of the same intermittently rotate the shafts to which they are connected, springs mounted on shafts adjacent this 30 shaft and sleeve which is located thereon, means connecting the said shafts for the purpose of assisting in the rotation of the shaft and sleeve which is located thereon, disks keyed to the shaft and the sleeve which 35 is rotatable thereon, pins extending from the opposite faces of the said disks, springs secured to a platform carried by one of the said plates, the said springs lying in the path of the said pins, a bell or bells electrically connected to said springs and adapted 40 when the springs engage the pins to audibly indicate the time of the clock by the completion of the electrical current through the pins, disks and shafts upon which said disks 45 are journaled, substantially as and for the purposes hereinbefore described.

In testimony whereof I affix my signature in presence of two witnesses.

FRED MICHAELIS.
